UNITED STATES PATENT OFFICE.

JAMES McNAMARA, OF MONTREAL, QUEBEC, CANADA, ASSIGNOR TO MERGENTHALER LINOTYPE COMPANY, A CORPORATION OF NEW YORK.

MONOLINE-MACHINE.

951,654.

Specification of Letters Patent. Patented Mar. 8, 1910.

Application filed November 7, 1908. Serial No. 461,522.

To all whom it may concern:

Be it known that I, JAMES McNAMARA, a citizen of the United States, residing in Montreal, in the Province of Quebec, Dominion of Canada, have invented a new and useful Improvement in Monoline-Machines, of which the following is a specification.

My invention has reference to that class of machines for casting printing bars or slugs, which are commonly known under the trade mark "Monoline" and represented as to their general organization in Letters Patent of the United States to Scudder, No. 605,141. In these machines, a series of circulating matrices, each containing from ten to twelve characters, is stored in a magazine, from which they are released one at a time by finger-keys and thereafter assembled in line, the keys representing the individual characters serving also to set stops by which each matrix is arrested at the proper level to bring the designated character to the alining level. As heretofore constructed, the matrices were divided into eight groups which carried only the characters for a single font. In the present state of the art it is desirable that the machine should carry two fonts or sets of characters of different sizes or styles, so that each line may be composed at will of characters from either or both fonts.

The object of my invention is to provide the machine referred to with matrices representing two fonts of characters without general reconstruction or rearrangement of its parts, and without increasing the size of the keyboard. To this end I provide the machine with an increased number of magazine channels and devices for delivering matrices therefrom, and with an increased number of matrices, and I connect the finger-key mechanism with the matrix-releasing devices through intermediate connections of such character that the finger-keys may be caused at will to actuate devices for delivering the matrices of either font.

I have limited the accompanying drawings to those parts which are more immediately associated with my improvement. It is to be understood that as to all other parts, the machine may be constructed in a manner represented in the patent above referred to, or in any equivalent manner.

Referring to the drawings,—Figure 1 is a vertical section from front to rear through

one of the magazine channels, the mechanism for discharging the matrices, and the finger-key connections. Fig. 2 is a top plan view of the magazine. Fig. 3 is a side elevation of the same together with other parts shown in Fig. 1. Fig. 4 is a front elevation of the parts shown in the preceding figures looking in the direction of the arrows in Figs. 2 and 3. Fig. 5 is a plan view of the shifting connections used between the finger-keys and the matrix-discharging devices, as adjusted to deliver from one set of magazine channels. Fig. 6 is a similar view with the parts adjusted to deliver from the other or intermediate set of channels. Fig. 7 is a perspective view of parts shown in the preceding figures. Fig. 8 is a side elevation of the finger-key mechanism and the shifting connections. Fig. 9 is a vertical section on the line 9—9 of the preceding figure. Figs. 10 and 11 are vertical sections showing on a larger scale one of the shifting connections in its two positions. Fig. 12 is a side elevation of one of the matrix bars.

The matrix bars A employed in my machine, are of the form shown in Fig. 12, each consisting of an upright bar provided with a suspending hook at the upper end, with a series of independent matrix characters one above another in one edge, and a corresponding series of alinement notches in the opposite edge. In the machine as formerly constructed, there were eight groups of matrices, the matrices in each group carrying the same twelve characters. In my improved machine I have increased the number of channels in the magazine and the number of groups of matrices, thus increasing the number of characters represented in the machine. Matrices of the same font are stored in alternate channels of the magazine, and the releasing devices and the finger-key mechanisms are so combined and arranged that when either font is in use, the matrices will be delivered from the alternate channels only. This arrangement of the matrices of two fonts in alternate channels in the magazine is attended with many advantages and is, I believe, wholly new in the art.

Referring to Figs. 2 and 3 of the drawings, 1, 2, 3, etc., represent parallel vertical matrix bar chambers into which the respective groups of matrices are delivered in a vertical position by the distributing mech-

anism of the machine. The delivery ends of these chambers terminate in separate narrow channels 12, which extend at right angles to the chambers to the front of the machine. The matrix bars are delivered 5 from the chambers into each of the channels 12 one after another, the matrices in each channel standing edge to edge in an upright position. The matrix bars in each 10 channel are urged forward toward the delivery point, as shown in Figs. 1 and 3, by an upright arm 15 in a horizontal sliding delivery gate 13, the front end of which 14 stands normally under the foremost matrix 15 for the purpose of sustaining the same,—the remaining matrices in the row being supported on the stationary floor or bottom 20 of the channel. Each gate 13 is held normally forward by a pawl 17 engaging a projection 19 on the gate, and when this pawl is disengaged, the gate is drawn suddenly backward by a spring 16 connected thereto, the effect being to release the foremost matrix and permit it to descend by 25 gravity toward the line assembling devices, the arm 15 being at the same time carried rearward in order to permit another matrix to enter the channel. After the delivery of a matrix, the gate 13 is instantly restored 30 to its original position by a dog 28 on the upper end of the oscillator 23, mounted on a pivot 24 and provided with a rotating cam 26 which is acted upon by a constantly turning roll 36 mounted in fixed bearings. 35 The roll causes the rotation of the cam, which in turn moves the oscillator against the resistance of spring 59 acting through a sliding pin on the oscillator. The delivery gate 13 being thus restored to its 40 original position, is again engaged and held by the pawl 17. As the gate 13 moves rearward to release a matrix, it acts on the lower end of an accelerating lever 22, the forward end of which acts to drive the matrix downward with speed and certainty. The gate-retaining pawl 17 is released by a lever 20, 45 actuated by a slide 20^a, connected to a finger-key E, the depression of which results in the delivery of a matrix.

50 In the original machine, the lever 20 acted directly on the pawl 17, as shown in Figs. 5 and 6 of Patent No. 605,141. In the present machine, I have interposed between each of the levers 20 and the corresponding pawl 17, fingers B hereinafter fully described. 55 With the exception of these interposed fingers, the parts so far as described are constructed and arranged to operate in the same manner as the parts indicated by like numerals in the original patent.

60 Referring now to my improvement, attention is directed to Figs. 2, 3 and 4. In the original machine, matrix chambers 1 to 8 only were provided, together with a corresponding number of channels 12. I have

now added to the machine similar chambers 8^a, 8^b, 8^c, 8^d, 8^e and 1^a and corresponding channels 12. The number of chambers and channels may be increased still further if desired, but in practice I find that the number shown, when supplied with corresponding groups of matrices, having fourteen characters each, is sufficient to provide the machine with two complete alphabets or fonts of characters, including upper and lower case, letters, numerals, punctuation marks, etc. The two fonts will ordinarily contain like characters having different forms or sizes. For example, the characters of one font may be a light face and the other a dark or bold face, or one may be composed of vertical and the other of italic characters. For each of the additional channels I provide a corresponding delivery gate 13 and all the connected parts for controlling 75 and operating the same, as in the case of the other channels, to effect the delivery of matrices. Instead, however, of providing a finger-key and its connections for each character represented in the matrices, I arrange 80 the matrices of one font in alternate channels, and the matrices of the other font in the intermediate channels, and I arrange between the original group of finger-keys and the latches 17 the laterally shiftable vertically acting fingers B, which may be adjusted to connect the releasing levers 20 with the latches 17 to release the matrices of one font or the other at will. The action of 85 these fingers is clearly shown in Figs. 10 and 11. Each finger is narrow at the top and wide at the bottom. When moved to the left as shown in Fig. 10, it serves as a connection between the releasing lever 20 and one of the latches 17 for releasing matrices of one font. When shifted to the right as shown in Fig. 11, it serves to operate the 90 latch to the right of the one previously actuated, to release matrices of the other font. The entire series of fingers are pivoted, as 95 shown in Figs. 5, 6 and 7, to a horizontally sliding plate b, guided in the frame of the machine and controlled by a horizontal finger-key or switch b', which is pivoted to the frame at b^a. The movement of this lever in one direction or the other shifts the 100 entire series of fingers B, and thus enables the finger-keys E to deliver matrices of one font or another, as demanded.

If desired, means may be provided for locking the switch or finger-key b' in its 105 position. A simple device for this purpose, shown in Figs. 5 and 6, is a latch b^a, pivoted at one end to the frame and containing a spring-actuated plunger b^c, which may be moved to and fro, as shown by dotted lines in said figures. These means, in addition to holding the parts in set position, subserve another valuable function,—namely, they 110 permit a temporary connection to be man-

120
125
130

ually made between the finger key mechanism and the other font, without disturbing the set relations, if for instance it be desired to employ one or more characters from the other font, but not enough characters to warrant the loss of time involved in a change of the set position; after which the parts are automatically restored thereto. Thus, for example, taking the set position illustrated in either Fig. 5 or Fig. 6, if it be desired to employ one or more characters from the font not in action, it is necessary merely to press the switch in the proper direction, which movement is permitted by the yield of the spring actuated plunger, and then to hold the switch in its abnormal position while the appropriate letter keys are struck, after which, upon the release of the switch, the spring acts to return it automatically to the set position.

The machine is provided, as heretofore, with a series of horizontal stop bars 56^a, actuated by pins on the slides 20^{1/2} to arrest the descending matrices at different heights to bring the selected characters to the alining level. These features and all their connections are foreign to my invention and may be of the construction shown in the original patent, or of any other suitable construction.

While I prefer to employ the fingers B in the form shown, it will be evident to the skilled mechanic that their form and arrangement may be widely modified without changing their mode of action or passing beyond the scope of my invention. The only requirement is a shiftable connection between one finger-key and the two mechanisms to release the matrices from adjacent channels.

By means of my improvement, the old machine is adapted by very slight additions, to compose lines of matrices from either of two fonts, or matrices in part from one font and in part from the other.

Matrices of the form herein shown, each containing a series of characters, are commonly known in the art as "multiple letter matrices," and it is with this meaning that the expression is used in the following claims.

Having thus described my invention, I claim and desire to secure by Letters Patent—

1. In a machine for producing type bars, matrices for two fonts arranged in alternating groups, means normally tending to deliver the matrices from the respective groups, holding devices for the said delivering means, a series of finger keys, and means whereby said keys may be connected at will with the alternate holding devices for one font or the other.

2. In a line casting machine, a series of matrix containing channels, two fonts of 65 matrices, those of each font arranged in

alternate channels of the magazine, means normally tending to deliver the matrices from the individual channels, holding devices for the said delivering means, a finger key mechanism and means movable at 70 will for connecting all the finger keys with the holding devices of one font or the other, as demanded.

3. In a machine of the class described, two matrix delivering gates 13 and their retaining pawls 17, in combination with a finger key, and a finger B shiftable at will to form a connection between the finger key and either of the pawls, whereby the actuation of the finger key releases either of the 80 delivering gates as may be desired.

4. In a line-casting machine, a series of magazine channels, the finger-keys and the levers 20 actuated thereby, in combination with the gates 13, their retaining pawls 17, 85 and the shiftable fingers B connecting the levers with alternate pawls.

5. In a machine of the class described, a magazine containing a series of channels side by side and two fonts of matrices divided into groups, the groups of each font located in alternate channels, in combination with means normally tending to deliver the matrices from the channels, holding devices for the said delivering means, 90 and connections operative at one time for acting upon the holding devices so as to release the matrices from the alternate channels only, and movable at will to act upon the holding devices and release the matrices 95 from the intermediate channels only.

6. In a machine for producing type bars, a series of matrix containing channels, two groups of multiple letter matrices arranged in alternate channels, means for releasing 105 the matrices from the respective group, means for arresting them at different levels, a series of finger keys, and means whereby said keys may be connected at will with the alternate releasing devices for one group 110 or the other.

7. In a line casting machine, a series of matrix containing channels, two fonts of multiple-letter matrices therein, those of each font arranged in alternate channels of 115 the magazine, means for releasing the matrices from the individual channels, means for arresting them at different levels, a finger-key mechanism, and means movable at will for connecting all the finger-keys 120 with the releasing devices of one font or the other, as demanded.

8. In a machine of the class described, a magazine containing a series of channels side by side and two fonts of multiple-letter matrices divided into groups, the groups of each font located in alternate channels, and means for arresting the matrices at different levels when released, in combination with matrix releasing devices 130

and connections operative at one time for releasing matrices from the alternate channels only, and movable at will to release the matrices from the intermediate channels 5 only.

9. In a machine of the class described, a plurality of matrix releasing means in combination with a finger key and an attached device operating in proximity to the several releasing means but not in contact therewith, together with an interponent shiftable at will to fill the space between the said operating device and any selected one of the matrix releasing means.

10. In a composing machine of the monoline type, the combination of a plurality of series of magazine pawls for controlling the delivery of matrices of different fonts, corresponding series of devices for controlling the movements of said pawls, arranged in a row, the controlling devices of one series alternating with those of another series, a key board, and devices operated by the key board and each common to pawl controlling 25 devices for more than one series whereby matrices of one of a plurality of fonts may be selected and delivered.

11. In a machine of the class described, the combination of a plurality of fonts of 30 matrices and finger key mechanism, with devices that may be set and locked to bring any selected font into operative relation with the finger key mechanism, the said devices comprising yielding means which permit them to be shifted at will, and without displacing the locking element, from their set position to effect a temporary operative relation between the finger key mechanism and one of the other fonts.

40 12. In a machine of the class described, the combination of a plurality of fonts of matrices and finger key mechanism, with devices that may be set and locked to bring any selected font into operative connection 45 with the finger key mechanism, the said devices comprising spring actuated means

which not only permit them to be shifted at will from their set position to effect a temporary connection between the finger key mechanism and one of the other fonts, but 50 also act to return them to their set position.

13. In a machine of the class described, the combination of a plurality of fonts of matrices and finger key mechanism, with devices that may be set and locked to bring 55 any selected font into operative connection with the finger key mechanism, which said devices may be shifted at will from their set position to effect a temporary connection between the finger key mechanism and one of 60 the other fonts, together with automatic means to return them to their set position.

14. In a machine of the class described, the combination of a plurality of fonts of 65 matrices and finger key mechanism, with devices which may be set and locked to connect one of the fonts with the finger key mechanism, the said devices being shiftable from their set position at will to effect a temporary connection between the finger 70 key mechanism and one of the other fonts, together with automatic means to return them to their former position.

15. In a machine of the class described, the combination of a plurality of fonts of 75 matrices and finger key mechanism, with devices which may be set and locked to effect an operative relation between one of the fonts and the finger key mechanism, the said devices being shiftable from their set position at will to effect a temporary operative relation between the finger key mechanism and one of the other fonts, together with automatic means to return them to their former position.

In testimony whereof I hereunto set my hand this thirtieth day of October, 1908, in the presence of two attesting witnesses.

JAMES McNAMARA.
